The file of this patent contains at least one drawing/photograph executed in color. Copies of this patent with color drawing(s)/photograph(s) will be provided by the Office upon request and payment of the necessary fee.
FIG. 1 is a front view of a display or portion thereof with graphical user interface showing the claimed design; and, FIG. 2 is another embodiment thereof.
The broken lines in the figures show a display or portion thereof, and form no part of the claimed design.

CLAIM
The ornamental design for a display or portion thereof with graphical user interface, as shown and described.
DESCRIPTION
1 Claim, 1 Drawing Sheet
(1 of 1 Drawing Sheet(s) Filed in Color)
